UNITED STATES PATENT OFFICE

NATHAN SCHWARTZ, OF NEW YORK, N. Y.

BLADE SHARPENER

Application filed October 8, 1930. Serial No. 487,312.

This invention relates to a sharpening device for edged tools, and is in the nature of an improvement upon my copending application, filed August 29, 1930, bearing Serial 5 No. 478,729.

The present invention aims to generally improve a sharpening device of the indicated character by providing one of a plurality of elements having concave surfaces of relatively different characters, respectively with circumferentially extending corrugations or undulations, by virtue of which a more rapid and effectual sharpening of the edges is accomplished.

15 The invention further aims to provide in a device of the indicated character, an element presenting a surface for initially honing or sharpening which is convex on its major portion and is provided with a remaining flat portion by virtue of which various forms of edged tools may be sharpened thereon.

As a still further object, the invention resides in a sharpening device including a casing 25 of cross sectionally elliptical tubular configuration, designed to receive two or more elements presenting substantially concave sharpening surfaces of different characters, which elements are removably associated with 30 the casing, in event of their renewal or replacement, when necessary.

Other objects of the invention reside in the comparative simplicity of construction and mode of use of the device, the economy with 35 which the same may be provided and the general efficiency derived therefrom.

With the above recited and other objects in view, reference is had to the following description and accompanying drawings, in 40 which there is exhibited one example or embodiment of the invention, while the claims define the actual scope of the same.

In the drawings:

Figure 1 is a perspective view illustrating 45 the sharpening device constructed in accordance with the invention and the manner in which the same is used.

Figure 2 is a transverse sectional view therethrough taken approximately on the line 50 2-2 of Figure 3.

Figure 3 is a longitudinal sectional view taken approximately on the line 3-3 of Figure 2.

Referring to the drawings by characters of reference, 5 designates generally a cross sectionally elliptical tubular casing of any suitable material, such as metal or hard rubber, which is provided at one end with an inwardly extending marginal flange 6 and which is provided with opposite inwardly 55 projecting longitudinally extending ribs or beads 7. A pair of sharpening elements designated respectively by the reference characters 8 and 9 are designed to snugly fit within the casing 5 between the ribs or beads 7. 60 The flange 6 serves as an abutment means at one end of the casing 5 for limiting the insertion of the elements 8 and 9 within the casing and preventing displacement thereof through the flanged end. The element 8, 70 which is preferably of glass, has its concaved inner sharpening surface 10 formed with circumferentially extending undulations or corrugations 11 which are extremely shallow but which function to more rapidly and effectually sharpen and finish the cutting edges of a blade when the same is reciprocated laterally 75 thereafter.

The element 9, which is preferably of stone, 80 has its inner surface 12 for the major portion thereof concave, the remaining portion 13 being flat. This affords surfaces of varying contours for use in connection with edged tools of various types. For instance, a double-edged safety razor blade will be 85 sharpened on the surface 12 of the element 9 by reciprocating the same laterally in the manner illustrated in Figure 1, while the blades of knives, scissors or the like may be sharpened on the flat surface 13 of the element 9 by either a longitudinal, transverse or 90 rotary movement.

While there has been illustrated and described a single and preferred embodiment of the invention, it is to be understood that 95 no limitation is necessarily intended to the precise structural details, but that variations and modifications which fall within the scope of the claims may be resorted to when desired.

What is claimed is:

1. In a blade sharpening device, a cross sectionally elliptical tubular casing having longitudinally extending ribs projecting inwardly from the sides of the casing which are of lesser radius, a marginal inwardly projecting flange at one end of said casing and a pair of semi-elliptical sharpening elements removably fitted within the casing respectively on opposite sides of the ribs and in abutting relation to the marginal end flange.
2. In a blade sharpening device, a cross sectionally elliptical tubular casing having longitudinally extending ribs projecting inwardly from the sides of the casing which are of lesser radius, a marginal inwardly projecting flange at one end of said casing and a pair of semi-elliptical sharpening elements removably fitted within the casing respectively on opposite sides of the ribs and in abutting relation to the marginal end flange, said elements being of different characters.
3. In a blade sharpening device, a cross sectionally elliptical tubular casing having longitudinally extending ribs projecting inwardly from the sides of the casing which are of lesser radius, a marginal inwardly projecting flange at one end of said casing and a pair of semi-elliptical sharpening elements removably fitted within the casing respectively on opposite sides of the ribs and in abutting relation to the marginal end of flange, one of said elements being of glass and having an undulating sharpening surface.
4. In a blade sharpening device, a cross sectionally elliptical tubular casing having longitudinally extending ribs projecting inwardly from the sides of the casing which are of lesser radius, a marginal inwardly projecting flange at one end of said casing and a pair of semi-elliptical sharpening elements removably fitted within the casing respectively on opposite sides of the ribs and in abutting relation to the marginal end flange, one of said elements having a sharpening surface, the major portion of which is concave and the remaining portion of which is flat.
